UNITED STATES PATENT OFFICE.

SIMON COOK, OF EAST AKRON, OHIO.

STEAM-TURBINE.

No. 842,083.

Specification of Letters Patent.

Patented Jan. 22, 1907.

Application filed November 14, 1906. Serial No. 343,425.

To all whom it may concern:

Be it known that I, SIMON COOK, a citizen of the United States of America, residing at East Akron, in the county of Summit and State of Ohio, have invented new and useful Improvements in Steam-Turbine Wheels, of which the following is a specification.

This invention relates to steam-turbine wheels; and one of the principal objects of the same is to provide a turbine-wheel of simple construction, which will operate economically, and which is composed of few parts, and which will operate efficiently in either direction.

Another object of my invention is to provide a turbine-wheel which may be operated by means of steam, water, hot air, or other power and which can be quickly reversed to rotate in opposite directions.

These and other objects may be attained by means of the construction illustrated in the accompanying drawings, in which—

Figure 1 is a central vertical section of a turbine-wheel made in accordance with my invention. Fig. 2 is a transverse section on the line 2 2, Fig. 1. Fig. 3 is a vertical section on the line 3 3, Fig. 1.

Referring to the drawings for a more particular description of my invention, the numeral 1 designates a cylinder which is composed of disks or cylinder heads 2 and an intermediate flanged rim 3, said rim having outwardly-extending flanges 4, which are connected by bolts 5 to the cylinder-heads 2.

A base 6 is formed upon the intermediate rim 3, and at the upper portion of said rim a solid extension 7 is formed. Extending tangentially through said extension 7 are the diverging inlet-openings 8, and connected to the outer ends of said openings 8 is a branch pipe 9, one branch of which enters one of the openings 8 and the other branch communicates with the other opening. The inlet-pipe 10 and the branch pipe 9 are connected to a suitable valve 11, by means of which steam or other power may be admitted to either branch 9 through the openings 8 to the rotary piston 12. The piston 12 is provided with a central shaft 13, said shaft

extending through stuffing-boxes 14 upon the opposite sides of the cylinder-heads 2, and a pulley 15 is secured to said shaft for a belt to lead to the device to be operated by the turbine. The piston 12 has formed upon its periphery a radially-extending zigzag central flange 16, and alternately arranged on

opposite sides of said flange are a series of abutments 17, said abutments being disposed in line with the apices 18 of the zig-zag sections of the flange 16. The exhaust-port may be located at any suitable point, but as shown in Figs. 1 and 3 is formed in the projecting portion 7 of the rim 4, as indicated at 19.

The operation of my invention may be briefly described as follows: When the valve 11 is turned to admit steam or other power through pipe 10 and through the pipe 9 at the left of Fig. 1, the steam passing through the opening 8 will impinge against the abutments 17 upon one side of the center of the piston and rotate said piston from right to left. When the valve is turned to admit steam through the right-hand opening in Fig. 1, the piston 12 is rotated in the opposite direction. The abutments 17 being located alternately on opposite sides of the piston and in transverse alignment with the apices 18 of the zigzag flange, the steam is discharged alternately upon opposite sides 80 of said flange against one of the abutments 17, which successively come into position to receive the impact of the steam or other power.

From the foregoing it will be obvious that my turbine-wheel is of simple construction, 85 is composed of few parts, which cannot readily get out of order, can be immediately reversed to rotate in opposite directions, can be produced at slight cost, and can be utilized for many purposes in the arts.

Having thus described the invention, what I claim is—

1. In a turbine-wheel, a casing, a piston adapted to rotate therein, said piston being provided with a radially-extending zigzag 95 centrally-disposed flange, and inwardly-extending alternately-arranged abutments.

2. A turbine-wheel comprising a casing, an intermediate rim extending around said casing between the cylinder-heads, and provided with outwardly-converging openings, a branch pipe fitted to said openings, an inlet-pipe, and an intermediate valve for placing the inlet-pipe into communication with either of said diverging openings, a rotary 105 piston mounted in said casing, said piston provided with a zigzag flange, and oppositely-located inwardly-extending alternately-arranged abutments.

3. A rotary turbine-wheel comprising a cylinder or casing consisting of cylinder-heads, and an intermediate flanged rim bolt

ed to said cylinder-head and provided with diverging inlet-openings, and a piston in said cylinder provided with a zigzag flange, and abutments extending inwardly and arranged alternately, said abutments being disposed in transverse alinement of the apices of the zigzag flange, substantially as described.

In testimony whereof I affix my signature in presence of two witnesses.

SIMON COOK.
